MICROMETER LAPPING FIXTURE

Elmer W. Pearson, Red Wing, Minn.

Application June 8, 1945, Serial No. 598,325

5 Claims. (Cl. 51—217)

1

This invention relates to a portable micrometer fixture or support, designed for supporting a micrometer during the operation of lapping the micrometer anvil and end of micrometer spindle.

An important object of the invention is to provide a device of this character which may be adjusted for use in accurately lapping anvils or spindles of micrometers of various sizes.

Another object of the invention is to provide a fixture having means whereby the micrometer or spindle thereof, is clamped in such a manner that an adjustment between the lap and the work being lapped, may be made, without disturbing the relative alignment of either.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings

Figure 1 is an elevational view of a fixture or support, constructed in accordance with the invention.

Figure 2 is a fragmental sectional view, illustrating the main column and adjustable sleeve movable over the column.

Figure 3 is a sectional view taken on line 3—3 of Fig. 1.

Figure 4 is a sectional view taken on line 4—4 of Fig. 1.

Fig. 5 is a plan view of the device.

Figure 6 is a side elevational view of the device, taken at right angles to Fig. 1.

Referring to the drawings in detail, the reference character 5 designates the base of the fixture, from which rises the column 6, the column 6 being secured to the base 5, and held in a vertical position, by means of the cap screw 7, that extends through an opening in the base and is embedded in the threaded bore 8 formed in the lower end of the column 6, as clearly shown by Fig. 6 of the drawings. The column 6 is provided with a key-way 9 which is disposed longitudinally thereof, the key-way being designed to accommodate the key 10 that is fitted in a groove, disposed in the inner surface of the sleeve 11, the key 10 being secured to the sleeve 11, by means of the pin 12, so that the sleeve may move longitudinally of the column 6, but be prevented from rotating with respect thereto.

Formed integral with the sleeve 11, and dis-

2

posed near the upper end thereof, is a plate 13 that is horizontally disposed, the plate being provided with an opening to receive the cap screw 14 that is of a length to extend into a threaded opening of the ground steel block 15, securing the block 15 to the plate 13. The front edge of the block 15 is formed with a V-shaped groove 16 in which the barrel of the micrometer under treatment, is held. A clamp 17 which is in the form of a bar adapted to span the V-shaped groove, is secured to the block 15, by means of the set screws 18, to the end that the barrel of a micrometer positioned within the V-shaped groove 16, will be firmly clamped within the groove and held against movement, during the lapping operation. Secured at the upper end of the column 6 by means of the cap screw 19 is a plate 20, which has an offset portion 21 formed with an opening for the reception of the sleeve 22 that is provided with external threads that cooperate with the internal threads of the sleeve 23 which is formed with a knurled end 24 by means of which the sleeve 23 may be rotated. The sleeve 22 is also formed with a knurled portion so that this sleeve may be rotated within the sleeve 23. The sleeve 22 is formed with an annular groove 25 into which the screw 26 extends, locking the sleeves 22 and 23 together, eliminating back-lash with plate 20, when the sleeves are operated.

The sleeve 22 is provided with fine, internal threads, that mesh with threads at the upper end of the adjusting rod 27 that has its lower end extended through an opening formed in the offset portion 28 of the plate 13, there being provided a clamp screw 29 positioned in a threaded opening formed in the edge of the offset portion 28 of the plate 13, the clamp screw contacting with the rod 27 in securing the plate 13 and rod 27, together. Thus it will be seen that due to this construction, the clamp screw 29 may be loosened, and the sleeve 11 adjusted longitudinally of the column 6. After the adjustment has been made, the clamp screw 29 may be operated to clamp the rod 27, securing the sleeve 11 in its position of adjustment. Should it be desired to further adjust the sleeve to a minute degree, the sleeve 22 may be rotated to raise or lower the rod 27 and sleeve 11 connected therewith.

Mounted on the base 5, are parallel lap supports 30 which are secured in position by means of the screws 31 that have their heads countersunk in the upper surfaces of the lap support 30.

Disposed between these lap supports 30, is a guide including the upwardly curved arm 32

that has a downwardly extended supporting pin 33 positioned within the opening 34 formed in the base. It will of course be understood that there will be a precise sliding fit between the pin 33 and opening 34 to insure accuracy during the lapping operation.

At the upper end of the arm 32 is an enlargement 35 formed with a horizontal bore to accommodate the pin 36 that extends from the yoke 37, the yoke 37 being formed with threaded openings to accommodate the set-screws 38 that are adapted to clamp the anvil end of the frame of a micrometer therebetween.

When positioning a micrometer frame in the device, the narrow end of the micrometer frame is positioned within the V-shaped groove 16 of the ground steel block 15, where it is held in position by means of the clamp 17. The sleeve 11 is now adjusted so that the anvil end of the micrometer frame will move between the arms of the yoke 37, where it will be clamped by the screws 38 and held securely in position.

The lapping tool, which in the present showing is indicated by the reference character A, is now positioned on the upper edges of the parallel lap supports, the intermediate portion of the lapping tool contacting with the anvil of the micrometer. By moving the lapping tool over the anvil, the anvil will be lapped and conditioned for accurate measurements.

It might be further stated that a knurled screw 39 extends through the enlargement 35 of the arm 32 and engages the pin 36 of the yoke 37, securing the yoke within the opening of the enlargement 35.

During the lapping operation, should it be desired to raise the anvil end of the micrometer to contact the lapping tool A, it is only necessary to rotate the sleeve 22 slightly, to the end that the sleeve 11 will be elevated, and since the lower end or anvil end of the micrometer frame is held within the yoke 37, the yoke 37 will be elevated by the vertical movement of the supporting pin 33 within the opening 34.

What is claimed is:

1. A micrometer lapping fixture, comprising a base, a column rising from the base, a block mounted for adjustment longitudinally of the column, means for securing the block in its positions of adjustment, means for adjusting the block longitudinally of the column, said block having a V-shaped groove in the face thereof, means on the block for clamping a micrometer barrel in the groove, means for clamping the anvil end of the micrometer to the base, and parallel supports providing a rest for a lapping tool used in lapping the micrometer anvil held between said rests.

2. A micrometer lapping fixture comprising a base, a vertical column rising from the base, a

sleeve mounted for longitudinal sliding movement on the column, a block having a V-shaped groove, mounted on the sleeve, an adjusting rod, means for connecting the sleeve and adjusting rod, means for moving the adjusting rod vertically adjusting the position of the block with respect to the base, said V-shaped groove adapted to receive a micrometer barrel, means for securing the anvil end of a micrometer to the base, and supports on which a lapping stone rests in lapping the anvil of a micrometer.

3. A micrometer lapping fixture, comprising a base, a column rising from the base, a sleeve movable longitudinally of the column, an adjusting rod supported by the column and disposed in parallel spaced relation with the column, means for connecting the adjusting rod to the sleeve for adjusting the sleeve vertically, a block to which the anvil end of a micrometer is secured, means for securing the block to the sleeve, a vertically movable member mounted on the base and including a yoke adapted to grip the anvil end of a micrometer supporting the anvil of the micrometer in lapping relation with the base, lapping tool supporting means mounted on the base and adapted to support a lapping tool during the lapping of the anvil.

4. A micrometer lapping fixture, comprising a base, a vertical column rising from the base, a sleeve mounted for longitudinal sliding movement on the column, means for securing the sleeve in various positions of adjustment, said means including an adjusting rod connected with the column, said adjusting rod adapted to operate to adjust the sleeve longitudinally of the column, a block movable with the sleeve, said block having a V-shaped groove in the front edge thereof, means for clamping the barrel end of a micrometer within the groove, a vertically movable member mounted on the base and adapted to clamp the anvil end of the micrometer secured within the groove of the block, and means on the base for supporting a lapping tool used in lapping the anvil held in the device.

5. A micrometer lapping fixture comprising a base, a column extending from the base at right angles with respect thereto, a sleeve movable over the column, said sleeve being held against rotary movement, an adjusting rod, means for securing one end of the adjusting rod to one end of the column, means for connecting the adjusting rod to the sleeve whereby rotary movement of the adjusting rod operates to move the sleeve longitudinally of the column, means for connecting the barrel end of a micrometer, to the sleeve, a vertically movable member mounted on the base and adapted to clamp the anvil end of the micrometer, whereby the anvil may be lapped.

ELMER W. PEARSON.
